UNITED STATES PATENT OFFICE.

OSCAR H. PIEPER AND ALPHONSE F. PIEPER, OF ROCHESTER, NEW YORK.

DENTAL-ENGINE BRACKET.

1,377,432.

Specification of Letters Patent. Patented May 10, 1921.

Original application filed May 27, 1912, Serial No. 699,938. Divided and this application filed November 12, 1917. Serial No. 201,543.

To all whom it may concern:

Be it known that we, OSCAR H. PIEPER and ALPHONSE F. PIEPER, citizens of the United States, both of Rochester, in the county of Monroe and State of New York, have invented certain new and useful Improvements in Dental-Engine Brackets; and we do hereby declare the following to be a full, clear, and exact description of the same, 10 reference being had to the accompanying drawings, forming a part of this specification, and to the reference numerals marked thereon.

The prime object of the invention is to afford a practicable and simply constructed pulley guard of a type which is particularly adapted for dental engine brackets, involving pulleys for guiding a transmission belt or cable leading from a driving 20 motor to the hand piece. A further purpose of our improvement is to provide a compact arrangement, with readily controlled means for removing the guard from operative relationship with the pulleys, and retaining it either in its operative or inoperative 25 position. An additional object of the invention is to afford a connection between different parts of a dental engine bracket, to permit greater freedom of movement, and 30 at the same time provide a structure that is simple and entirely efficient in a practical way. To these and other ends the invention consists in certain improvements and combinations of parts, all as will be herein- 35 after more fully described, the novel features being pointed out in the claims at the end of the specification.

In the drawings:

Figure 1 is a side elevation of a portion 40 of a dental engine supporting arm, with parts appearing in section, and showing the application of the improvements;

Fig. 2 is an enlarged sectional view similar to that of Fig. 1, showing the guard in 45 its outermost or inoperative position;

Fig. 3 is a plan view of the guard in operative position;

Fig. 4 is a plan view of the guard withdrawn from operative position, and

Fig. 5 is a detail view in elevation.

Similar reference numerals in the several figures indicate the same parts.

This application is a division of an original application filed by us May 27, 1912, 55 Serial No. 699,938, and in the present em-

bodiment, 1 designates generally a supporting arm which carries a suitable hand piece to which power is supplied by a belt 2. The hand piece is pivotally arranged upon the supporting arm so as to have a limited 60 swinging movement axially of the supporting arm, and to this end the hand piece joint includes a central portion 3 to which is fixed a rod 4, and the latter extends through an opening in the outer end of the supporting 65 arm 1. Arranged upon the inner end of the rod 4 is a limiting means, preferably in the form of a plate 5, which is fixed upon the rod by a screw 6 and prevents separation of the supporting arm and hand piece joint. 70 7 designates a stop arranged for engagement with opposite faces 8 of the plate 5, whereby to limit its movement in opposite directions.

Arranged upon the central portion 3 of the joint is a pulley guard consisting of oppositely disposed guard portions 9 and a connecting body portion 10. The guard portions 9 are arranged to coöperate with pulleys 11 disposed upon opposite sides of the central portion 3 and mounted upon an 80 arbor 12. The guard is arranged upon a supporting pin 13 which is movable in the recess 14 of the central portion. The guard and the pin 13 are held normally in their innermost positions, as shown in Figs. 1 and 85 3, by means of a spring 15 which engages the head 16 of the supporting pin and acts to retain the latter in the position shown in Fig. 1.

The guard can be withdrawn against the 90 action of the spring 15, so as to be removed to a distance from the pulleys and permit access thereto and to the belt for adjustment of the latter as may be necessary, and in order to retain it in its outermost or inoperative 95 position, it carries a locking pin 17 which coöperates with a reduced recess 18 when in its innermost position. The recess 18 is preferably of just the size to receive the pin 17, and terminates at its outer end in 100 an enlarged seat 19 which permits a limited lateral movement of the locking pin 17, such lateral movement being determined by the side wall or edge 20 of the seat 19, as shown in Fig. 2. Thus by pulling the guard outwardly and turning it slightly about the axis of the supporting pin 13, the locking pin 17 is disengaged from the recess 18 and rests upon the bottom of the seat 19, as 105 shown in Figs. 2 and 4. To restore the 110

guard to normal position, a slight lateral movement is all that is necessary, bringing the pin 17 into alignment with the recess 18, whereupon the spring 15 restores the guard 5 into operative relationship with the pulleys.

We claim as our invention:

1. In a dental engine bracket, the combination of a supporting arm having a recess therein, a pulley rotatably carried on said 10 arm, a guard for said pulley having a portion rotatably and slidably carried in said recess in the arm, resilient means tending to slide said guard portion in said recess to maintain said guard in operative position adjacent said pulley, and coöperating parts 15 on said arm and guard whereby, upon sliding and rotating said guard portion in said recess in opposition to said resilient means, said guard may be retained in inoperative 20 position removed from said pulley.

2. In a dental engine bracket, the combination of a supporting arm having a recess therein, a pulley rotatably carried on said arm, a guard for said pulley comprising a 25 supporting pin rotatably carried in said recess and slidable therein to move said guard to and from operative position adjacent said pulley, a spring tending to slide said pin in said recess and maintain said guard in operative position, and coöperating parts on said arm and guard for retaining the latter in inoperative position brought into coöperating 30 engagement by rotation of said guard pin in said recess after sliding said pin therein to move the guard away from the 35 pulley.

3. In a dental engine bracket, the combination with a supporting arm, of a hand 40 piece joint including a central portion, pulleys disposed on opposite sides of said central portion, a supporting pin, a pulley guard mounted on said supporting pin, the pin being movable in a recess in the central portion, a spring arranged in said recess and coöperating with said pin to retain the 45

guard in operative position, and a locking pin carried by the guard and coöperating with said central portion, when the guard is withdrawn and turned, acting to hold it in its outer or inoperative position. 50

4. In a dental engine bracket, the combination with a supporting arm, of a hand piece joint including a central portion, pulleys disposed on opposite sides of said central portion, a supporting pin, a pulley guard mounted on said supporting pin, the pin being movable in a recess in the central portion, a spring arranged in said recess and coöperating with said pin to retain the guard in operative position, and a locking 55 pin carried by the guard, said central portion having a reduced recess to receive the locking pin when in its innermost position and an enlarged seat for the locking pin surrounding said recess at its outer end and 60 serving to receive the end of the locking pin and permit slight lateral movement thereof, said enlarged seat having a side wall which limits the lateral movement of the locking pin. 70

5. In a dental engine bracket, the combination with a supporting arm, of a hand piece joint including a central portion, pulleys disposed on opposite sides of said central portion, a supporting pin, a pulley guard mounted on said supporting pin, the pin being movable in a recess in the central portion, a spring arranged in said recess and coöperating with said pin to retain the guard in operative position, and a locking 75 pin carried by the guard, said central portion having an enlarged seat to receive and permit limited lateral movement of the locking pin when in outermost position, and a reduced recess at the center of said seat 80 which receives the locking pin when in its innermost position. 85
